ATTORNEY

UNITED STATES PATENT OFFICE.

HENRY WEIL, OF NEW YORK, N. Y.

COIN-RECEPTACLE.

1,243,467.

Specification of Letters Patent. Patented Oct. 16, 1917.

Application filed August 24, 1916. Serial No. 116,618.

To all whom it may concern:

Be it known that I, HENRY WEIL, a citizen of the United States, and resident of the city, county, and State of New York, 5 have invented certain new and useful Improvements in Coin-Receptacles, of which the following is a specification.

This invention relates to a coin receptacle of the type designed to prevent individual 10 or unauthorized withdrawal of the inserted coins, being intended more particularly for use as a savings bank for small coins; or "dime savings bank".

The invention has for an object the 15 production of a receptacle of this kind of cheap construction which will prevent withdrawal of the coins by shaking the receptacle or otherwise.

For further comprehension of the invention reference will be had to the following 20 description and accompanying drawing and to the appended claims in which the various novel features of the invention are more particularly set forth.

25 Figure 1 of the drawings is a face view, partly broken away to show the invention, of a coin receptacle embodying the invention.

Fig. 2 is a view partly side elevation and 30 partly transverse section on the line 2—2 of Fig. 1.

Fig. 3 is a view partly plan and partly horizontal section on the line 3—3 of Fig. 1.

My improved coin receptacle comprises a 35 casing or shell 1. This casing as here shown is constructed of flexible material, such as cloth or leather, and consists of two sheets, 2 and 3, of such material secured together along their edges, as by the line of stitching 40 4, the casing thus constituting a bag closed both on sides and top and bottom.

Formed in one side wall, 2, of the casing is an opening or slot 5 for the insertion of coins, this opening being preferably of only 45 sufficient size to permit of the insertion of the desired coins. Communicating with this slot or opening 5 is a chute 6 which extends into the receptacle, being preferably arranged to extend, in parallel relation to 50 the wall 2, first laterally from said opening and then downwardly. I prefer the above described arrangement of coin slot and chute since it more completely insures against improper withdrawal of the coins, although 55 other arrangements might be used with sat-

isfactory results. This chute is also preferably constructed of cloth, leather or other flexible material, and may be secured in place by forming flaps 7 and 8 on the laterally extending end of the chute, with flaps 60 extended through the opening in the wall 2 and stitched, as indicated at 9, to the wall 2 adjacent said opening, which latter they serve to reinforce.

To prevent the flexible chute being drawn 65 outwardly through the opening 5 or turned "inside cut" to effect a withdrawal of the coins, the chute is preferably also secured to the casing at a point removed from the said opening, or adjacent the inner end of 70 the chute, as indicated at 10.

It will be noted that the particular disposition of the chute and the flexible nature thereof render it impossible to remove the 75 coins by shaking the receptacle, this feature of preventing the unauthorized removal of the coins being obtained, as will be apparent, with a very simple and inexpensive construction.

If desired, the casing of the receptacle 80 may be made of metal or other rigid material and may be given any desired shape or configuration. Various other changes and modifications not herein specified may be made without departing from the spirit 85 of the invention and the right is therefore reserved to all such changes and modifications as come within the scope of the appended claims.

What I claim is:

1. A coin receptacle of the type described, comprising a closed bag made of flexible material and having a coin slot in one face thereof, and a chute of flexible material leading inwardly from said slot parallel to the 95 said face first sidewise and then downward between the opposite faces of the bag. 90

2. A coin receptacle of the type described, comprising a closed bag made of flexible material and having a coin slot in one face 100 thereof, a chute of flexible material leading inwardly from said slot parallel to the said face first sidewise and then downward between the opposite faces of the bag, and means attaching said chute to the bag at a 105 point near the lower end of the chute.

Signed at the city, county and State of New York, this 22d day of August, 1916.

HENRY WEIL.
